UNITED STATES PATENT OFFICE.

EDWARD H. CALLAWAY, OF NEW YORK, N. Y., ASSIGNOR TO THE AMERICAN CLAY MACHINERY COMPANY, OF EUCYRUS, OHIO, A CORPORATION OF OHIO.

COMBINED HIGH AND LOW PRESSURE VACUUM CIRCULATING SYSTEM FOR HEATING APPARATUS.

1,183,853.

Specification of Letters Patent.

Patented May 23, 1916.

Application filed October 10, 1911. Serial No. 653,864.

To all whom it may concern:

Be it known that I, EDWARD H. CALLAWAY, a citizen of the United States, residing at New York city, in the county of New York and State of New York, have invented certain new and useful Improvements in Combined High and Low Pressure Vacuum Circulating Systems for Heating Apparatus, of which the following is a specification, reference being had therein to the accompanying drawing.

My present invention relates to certain new and useful improvements in combined high and low pressure vacuum circulating systems for heating apparatus for brick driers and other purposes, the same having for its object economy in the construction and operation of a drying apparatus as well as greater efficiency and many other desirable characteristics.

The invention comprises certain novel and useful combinations of mechanical parts including steam heating pipes and a jet condensing device, the latter being so combined and arranged that a certain amount of live steam can be condensed as required to create a vacuum in the system, improve the water circulation and secure a great gain in economical operation of the apparatus.

The invention may be said, therefore, to consist essentially in the combination, construction and arrangement of the various parts, substantially as will be hereinafter described and claimed.

In the accompanying drawing illustrating my invention, Figure 1 is a perspective view of my improved heating apparatus. Fig. 2 is a vertical sectional detail on an enlarged scale of the jet condenser and adjacent parts. Fig. 3 is a detail plan view of the perforated partition in the upper part of the condenser shell.

Like characters of reference designate corresponding parts throughout the different figures of the drawing.

The pipe rack forming a part of one example of my improved drying apparatus is represented only partially, it being thought unnecessary to show the whole of

it. One end is delineated at the left in Fig. 50 1 where I have shown a pair of vertical pipes 3, 3, having the horizontal pipes 4 connected thereto, and another pair of vertical pipes 5, 5, having horizontal parallel pipes 6 connected thereto. The vertical 55 columns 3, 3, are connected at the upper end by a cross pipe 1 having an inlet 2 through which steam is admitted to the pipe rack from the boiler. This steam may be live steam or exhaust steam, and it obviously 60 passes into the vertical pipes 3 and then through the horizontal pipes 4 to the other end of the drier. The returning steam and the water of condensation pass through the other series of horizontal pipes 6 into the vertical pipes 5. The lower ends of the vertical pipes 3 are provided with pipes 11 and 12, pipe 12 passing out of the lower 65 part of one of the pipes 3, and pipe 11 out of the lower part of the other pipe 3, the 70 latter connecting with the pipe 12, which latter runs to the trap 17 and constitutes one of the circulating pipes leading to the jet condenser. From the lower end of one of the vertical pipes 5 passes a pipe 13, to 75 which connects another pipe 14 leading from the lower end of the other vertical pipe 5. Obviously, the pipes 14 and 13 receive the water which is returning from the pipe rack and is in the form of water of 80 condensation, and the pipes 13 and 14 connect with the pipe 15 which runs alongside of the pipe 12 and extends to the jet condensing apparatus forming a part of the 85 circulating system which I am describing, and by means of which a vacuum is created. On one pipe 6 leading to one of the vertical pipes 5 is a short pipe 7 which connects with a pipe 8 leading to one of the horizontal pipes 6 connecting with the other vertical 90 pipe 5, and pipe 8 carries an automatic air release valve 9 and is provided with a globe valve 10. Valve 10 is closed when the system is working under high pressure, and is open during low pressure operation. The 95 upper portions of the vertical pipes 3 and 5 are connected by the horizontal pipes 37 having control valves 38 thereon.

The pipe 12 leads to a trap 17, and from the trap 17 runs in the same direction as pipe 12, a pipe 12^a that enters the lower end of the vertical condenser shell 22. The pipe 15 which runs parallel to the pipe 12 does not connect with the trap 17, but enters the condenser shell 22 at a point opposite to where the pipe 12^a enters it as shown in Fig. 2. On the pipe 15 is a valve 18, to be closed when the system is operating under high pressure, near to which is a cross-pipe 30 which connects the two pipes 12 and 15 and is provided with a valve 31 that is closed during low pressure operation and open during high pressure. Furthermore, pipe 12 is provided with a blow-off pipe 32 having therein a valve 16. A live steam pipe 21 enters the pipe 15 and is provided with a valve 20 by means of which the supply of live steam to the pipe 15 and to the jet condenser 22 is controlled and regulated. It is obvious that the pipes 12 and 15 leading from the pipe rack convey the water of condensation running from the pipes of said rack and pass this water into the lower end of the condenser shell 22 whence it falls into a receiver 24, from whence it is removed by a pump 28 through a bottom outlet pipe 29. It will be understood that by opening the valve 20 in the live steam pipe 21 a greater or less amount of live steam can be introduced into the condenser shell 22 through the pipe 15, the same taking place at the beginning of the operation and during the low pressure action in order to create a vacuum.

The condenser shell 22 is simply a short cylindrical section of pipe placed in a vertical position and provided at its upper end with an interior perforated disk or diaphragm 23. Cold water is supplied through a pipe 34 which enters the upper end of the shell 22. Pipe 34 is provided with a hand valve 33 which controls the supply of water. On the side of the shell 22 is preferably a gage 35. The condensing water falls through the perforated partition 23 and is sub-divided into a small spray that dashes downwardly through the shell 22 and condenses whatever steam may be found therein entering through pipe 15. The water of condensation and the condensed steam pass together into the receiver 24, (although there may be circumstances where such receiver is dispensed with) and the water is removed directly by means of the pipe 29 and pump 28. When the receiver 24 is used I preferably employ a float valve 25 therein, which is carried by a pivoted lever 26 which operates a valve 27 in the steam pipe 36, and by this means the supply of steam is regulated and the operation of the pump 28 controlled, the pump being shut down when the water level drops to a certain degree and having its operation begin again when the

water level rises to the point where it is desirable to carry on the pumping.

When the system is operating with low pressure it will be evident that the valve 18 in the pipe 15 will be open, and the valve 31 will be closed. The jet condensing device will then be used whenever it is necessary by merely opening the valve 20, as I have already said, in order to allow a certain amount of live steam to enter the shell 22. When the system is operating under a high steam pressure, however, any supply of steam through the pipe 21 will not be needed, and consequently the pipe 15 will be cut out by closing the valve 18 and opening the valve 31, in which case the water of condensation will all reach the condenser through the pipe 12^a from the trap 17 after it has been delivered to said trap by means of the pipe 12.

I will now describe the operation of my improved high and low pressure vacuum system and point out how it is convertible from low pressure to high pressure and vice versa. Obviously, the steam which is supplied to the pipe rack through the pipe 2 may be live steam direct from the boiler or it may be exhaust steam. It will be exhaust steam during the day time when the engine is running, but at night live steam will be used. Further, the introduction of live steam into the condensing chamber 22, and the bringing of it under the action of spraying water in order to create a vacuum, is a plan which is utilized in this invention with great advantages. When the system is started up a certain quantity of live steam will be admitted through pipe 21, by opening valve 20, into pipe 15 and through it into the condenser shell 22. At this time, of course, the pipe 15 will be empty and the live steam will readily pass into the condenser. The condensation of the steam within the condenser by the shower of water falling through the perforated partition 23 will condense the steam and thereby create a vacuum, the effect of which will be felt through the whole system, and this will draw the steam, either live steam or exhaust steam, as the case may be, throughout all of the pipes of the pipe rack, and the other pipes of the system. At this time obviously, the system will be operating as a low pressure system, the valve 18 will be open, and the valve 31 in the connecting pipe 30 will be closed. After the low pressure system has operated a sufficient length of time to have the whole system properly filled, as shown by a steam gage at 36^b on the pipe rack, the jet condensing device can be cut out by closing the valve 18 and opening the valve 31, and thus the system will be changed from a low pressure to a high pressure system. Of course it can be changed back to a low pressure system whenever re-

quired. Thus I maintain the advantages of a combined high pressure and low pressure system to create the required vacuum. My system dispenses with the necessity of the 5 vacuum pump and the expensive traps and other appurtenances commonly employed, for I am able to create all the required vacuum in a short time by the simple utilization of live steam introduced to the condenser at the beginning of the operation when the condensation takes place. The 10 convertible character of the system from low pressure to high pressure is exceedingly valuable, for I am enabled to secure at one 15 time all the advantages of a low pressure operation and at other times those of a high pressure operation, and I again emphasize the point of using live steam and condensing it to form a vacuum instead of using the 20 expensive pumping systems heretofore commonly employed.

The trap 17 needs very little description because it is a well known factor in steam distribution. It is so placed that the water 25 of condensation flows into it by gravity from the pipe 12. When the valve 19 at the top of the trap is closed the discharge from the trap is shut off and it remains so until the float within the trap at 36^a becomes 30 nearly filled from the overflow of water into it, when its weight becomes such that it overcomes the tendency of an inner discharge valve (not shown) to remain closed, being held there by steam pressure, and it 35 drops to the bottom thereby opening a discharge valve. The valve action is purposely intermittent.

Although my invention is primarily designed for use with brick drying apparatus, 40 yet it is evident that it has a wider application and may be easily applied to many different kinds of heaters, as, for example, the heating of houses. The introduction of a greater or less amount of steam into the condenser and the condensation of such steam 45 enables the system to be operated in such a way that great economy is obtained, and simplicity and effectiveness characterize the entire system, thereby producing the best results in practice.

Having thus described my invention, what I claim as new and desire to secure by Letters Patent is:—

1. In a heating apparatus, the combination with heating surfaces, of means for supplying steam to said surfaces, a jet condensing means, means comprising pipes for removing the water of condensation from said surfaces and carrying it to the condenser, means for admitting through one of said pipes a quantity of live steam to the condenser to be condensed therein for the purpose of creating a vacuum in the system, a trap on one of said pipes, and a receiver into which the water passes from the

condenser, together with an automatic pump for removing the water from the receiver, the whole combined and arranged to operate either as a low pressure or a high pressure system. 70

2. In a heating apparatus, the combination with radiator means, of a jet condenser, pipes for leading the water of condensation into said condenser, means for admitting a certain quantity of live steam into 75 one of said pipes so that it may be condensed in the condenser when the apparatus is to operate under low pressure, a trap on one of the pipes leading to the condenser, and a receiver for receiving the 80 water of condensation and the condensed steam from the condenser, together with means for introducing condensing water in a spraying volume into said condenser in order to condense the steam and create a 85 vacuum.

3. In a heating apparatus, the combination of a pipe rack, means comprising pipes leading to the condenser for removing the water of condensation from said rack, and 90 means for admitting steam into the pipes of the rack, a condenser shell, means for shutting off one of the pipes leading from the condenser to the rack when the high pressure system is employed, means for admitting a greater or less amount of live steam 95 into the condenser shell when the apparatus is to be operated under low pressure, and a receiver for receiving the water of condensation and the condensed steam from the condenser, means for removing water from the receiver, and means for introducing condensing water into the shell so as to condense the steam and create a vacuum. 100

4. In a heating apparatus, the combination with steam distribution pipes, of a jet condensing device comprising a shell, means for admitting live steam into it, and means for condensing said live steam to create a vacuum, the whole combined and arranged so that the utilization of the condensing device may be had when the apparatus is operating under low pressure, means for cutting out said condensing device when the apparatus is operating at 110 high pressure, together with a receiver for removing the water of condensation from the condenser shell, and an automatic pump for removing the water from the receiver. 115

5. In a heating apparatus, the combination of heating surfaces, means for supplying steam thereto, a jet condenser, pipes leading from the heating surfaces for removing the water of condensation and conveying it to the condenser, a trap on one 125 of said pipes, means for admitting live steam in the other of said pipes so that it may pass into the condenser when the apparatus is to be operated under low pressure, means for introducing condensing water 130

into the condenser so as to condense the steam and create a vacuum, and means for cutting out said condensing device when the apparatus is operating at high pressure, together with a receiver for receiving water from the condenser, and means for removing water from said receiver.

In testimony whereof I affix my signature in presence of two witnesses.

EDWARD H. CALLAWAY.
